DESIGN FOR A SMOKING STAND

Frederick T. Paden, United States Army,
Collingswood, N. J.

Application April 18, 1945, Serial No. 119,079

Term of patent 7 years

(Cl. D85—2)

To all whom it may concern:

Be it known that I, Frederick T. Paden, Army of the United States, a citizen of the United States, residing at Collingswood, in the county of Camden and State of New Jersey, have invented a new, original, and ornamental Design for a Smoking Stand, of which the following is a specification, reference being had to the accompanying drawing, form a part thereof.

Fig. 1 is a side elevational view of a smoking stand showing my design.

Fig. 2 is a front elevational view of the smoking stand.

Fig. 3 is a top plan view of the smoking stand.

Fig. 4 is a section of the smoking stand taken along the lines 4—4 of Fig. 1.

I claim:

The ornamental design for a smoking stand, substantially as shown.

FREDERICK T. PADEN.
